UNITED STATES PATENT OFFICE.

EDWIN B. STIMPSON, OF BROOKLYN, NEW YORK, ASSIGNOR TO EDWIN B. STIMPSON COMPANY, OF BROOKLYN, NEW YORK.

ATTACHMENT FOR RIVET-DRIVING MACHINES.

Application filed November 26, 1921. Serial No. 517,919.

To all whom it may concern:

Be it known that I, EDWIN B. STIMPSON, a citizen of the United States, residing at Brooklyn, in the county of Kings and State of New York, have invented certain new and useful Improvements in Attachments for Rivet-Driving Machines, of which the following is a specification.

This invention relates to attachments for rivet-driving machines in which the shanks of the rivets are slit lengthwise to form bifurcations. It is an object of this invention to provide means whereby the slit rivets may be fed beneath the driving plunger of the machine so that the jaws or bifurcations of all of the rivets will be similarly positioned, i. e., all of the slits will occupy substantially the same plane, when in position to be driven by the plunger. Such an arrangement not only adds to the finished appearance of the article due to the symmetrical arrangement of the rivet jaws, but is in many cases absolutely necessary by the shape of the finished article. The present invention provides simple, effective means for accomplishing this object.

Other objects and advantages will hereinafter appear.

In the accompanying drawings:

Figure 1 is a front elevation of a portion of a rivet-driving machine with the invention applied thereto;

Figure 2 is a side view of the device shown in Figure 1;

Figure 3 is an enlarged detail view of the invention applied to the machine and showing the driving plunger in lowered position;

Figure 4 is a view similar to Figure 3 but showing the driving plunger in elevated position;

Figures 5 and 6 are views similar to Figures 3 and 4, respectively, but showing a modified form of the invention;

Figure 7 is a perspective view of the operating member in the form of the invention shown in Figures 1 to 4 inclusive;

Figure 8 is a front and a side elevation of the tip of the operating member shown in Figure 7;

Figure 9 is a plan view, partly sectioned, of the modified form of the invention shown in Figures 5 and 6.

Referring to the drawings, there is shown a rivet-driving machine of the usual type comprising a vertically-reciprocating plunger 10 operating between guides 11 to drive rivets such as 12 downwardly through an article 13 supported upon an anvil 14 in axial alignment with said plunger 10. On the downward stroke of the plunger a rivet is driven through article 13 and the jaws of the rivet are spread upon the opposite face of the article. The rivets are fed to the driving position beneath plunger 10 and between guides 11 in the usual manner by allowing the rivets to pass down an inclined guide-way 20, upon which they are supported by their heads, until they rest above a horizontal slot 21 in which operates a slide 22. Said slide has a vertical opening 23 therein large enough to receive the lowermost rivet in guide-way 20, and said slide is so connected with the plunger that every time the latter operates to drive a rivet into an article the slide is moved over until the rivet held therein is directly over an inclined slot 24 which terminates adjacent the plunger when the latter is in lowered position (see Fig. 3). When the plunger is elevated it rises above the lower end of slot 24 and permits the rivet held in the end of the slot to drop between guides 11 into the driving position. As the plunger descends, another rivet is fed by slide 21 into slot 24, said rivet moving to the lower end of slot 24 and abutting against the plunger. The action is then repeated. The hereinbefore described structure is usual in rivet-driving machines.

It is desirable, as previously pointed out, that the rivets be fed to the driving position with their jaws similarly positioned, i. e., with the slits in substantially the same plane. For this purpose there is provided a device which operates to position the rivets properly as each rivet reaches the bottom of slot 24 adjacent the lowered plunger in position to drop to driving position when the plunger is raised. Each rivet is similarly positioned by this device so that when it drops to driving position the plane of the slits will be in substantially the same position in every case. The device comprises an operating member in the form of a lever 30 pivoted at 31 to a bracket 32 fixed to the frame of a

rivet-driving machine. The lever 30 carries at its end a flattened portion 35 having a pointed tip 36, said portion when operated toward the machine contacting with the rivet 5 at the end of slot 24 waiting to be dropped to driving position when plunger 10 rises. By repeatedly operating portion 35 back and forth into and out of contact with the slit end of the rivet-shank, the tip, which is necessarily a wedge and twisted slightly to form a screw or spiral, works its way into the rivet slit, and the flat portion 35 exerts a camming action on the rivet until the plane of the slit coincides with the plane of the portion 35. The portion 35 may then operate in and out of the slit freely. The same action is exerted upon each rivet as it comes to position at the end of slot 24. By the time plunger 10 rises above the end of slot 20, lever 30 has been actuated back and forth several times and the rivet-slit has been brought into the plane of portion 35 by the camming action of said portion. Each rivet 25 is therefore similarly disposed as it drops to driving position beneath the plunger.

To operate lever 30 intermittently, there is provided a rod 40 having engagement at one end with plunger 10 and at the other end with an arm 41 carried by lever 30. As the plunger 10 rises, a series of corrugations formed thereon comes into contact with rod 40 and drives said rod inwardly and outwardly. The intermittent movement of rod 40 is transmitted to lever 30 through arm 41 causing portion 35 to strike successively against the end of the rivet at the lower end of slot 24. The tip 36 of portion 35 is so positioned that it will enter the slit in the rivet-shank when lever 30 is actuated. The 40 repeated, intermittent blows cause the screw or spiral tip 36 and portion 35 to work their way up into the rivet slit, said tip turning the rivet so that the plane of the slit is in the plane of portion 35 before the plunger 45 has reached its uppermost position. The rivet is held against upward movement by its inclined temporary set against plunger 10. To absorb the blows which would be occasioned if tip 36 should strike the solid portion of the rivet-shank, the arm 41 is preferably of spring metal to absorb such shocks. Lever 30 may be held normally away from the rivet by a suitable spring, such as a coil-spring 30^a on pivot 31 in the usual manner. Rod 40 is normally pressed inwardly by a spring 45 in a housing 46 formed preferably in the machine frame. If desired, the corrugations 43 may increase in diameter from top to bottom on the plunger (as shown) so 60 that after the tip 36 and portion 35 have made an entry into the rivet slit, the throw of said portion may be increased.

A modification of the invention is illustrated in Figures 5, 6 and 9. A flat portion 50 similar to flat portion 35 and having a

point or tip 51 similar to tip 36 is fixed near one end of a spring member 52 whose other end is attached to the machine frame. The plunger 10 is provided with a pin 55, which, when the plunger rises, engages one arm 56 70 of a lever pivoted at 57 on the machine frame. The end of the other arm 58 of said lever engages a corrugated portion 59 formed in spring member 52, so that as the plunger rises, arm 58 will rotate downwardly from 75 a substantially horizontal position thus causing its end to move inwardly toward the machine and permitting portion 50 to move further into the rivet slit. As the end of arm 58 moves over the corrugations, the 80 portion 50 will be alternately pressed away from the rivet slit and permitted to spring into said slit, thus causing an intermittent movement similar to that caused by corrugations 43. When the plunger descends, a 85 spring of any ordinary type may be provided to restore arm 58 to its raised position, overcoming spring 52 to force the latter to ineffective (or Fig. 5) position.

Variations may be resorted to within the 90 scope of the annexed claims.

The structural features peculiar to the embodiment of Figs. 5 and 6 hereof are not herein claimed, but are fully disclosed and claimed in my co-pending application Serial 95 No. 632,715 filed April 17, 1923, and forming a division of this specification.

Claims:

1. The combination in a rivet-driving machine for rivets, each of which has a 100 slit lengthwise through the shank thereof to form bifurcations, said machine having means for feeding the rivets to a point adjacent the driving position, said means including a supply hopper, and guiding means for transferring the rivets in column from said hopper to said point but with the slits of the rivets non-aligned, of means for automatically acting on a rivet in the guiding means near the driving position, said means being operated by the driving means for aligning the slits of the successive rivets as each rivet is being initially advanced toward the said point, said positioning means including a movable member adapted correctly to align the rivet by engagement with said bifurcations.

2. In a rivet-driving machine having means for feeding the rivets to a point adjacent the driving position, each of said rivets having a slit lengthwise through the shank thereof to form bifurcations, means mounted upon said machine for positioning said rivets when adjacent the driving position so that the slits and the bifurcations of the rivets are similarly disposed, said means including a member and means for giving said member a plurality of back and forth strokes relative to each rivet as the same approaches driving position.

3. In a rivet-driving machine having means for feeding the rivets to a point adjacent the driving position, each of said rivets having a slit lengthwise through the shank thereof to form bifurcations, means mounted upon the machine for positioning said rivets when adjacent the driving position so that the slits and the bifurcations of the rivets are similarly disposed, said means including a flat member adapted to enter the slits in the rivets and means for giving said member an intermittent motion to cause said member to enter the slits in the rivets.
4. In a rivet-driving machine having means for feeding the rivets to a point adjacent the driving position, each of said rivets having a slit lengthwise through the shank thereof to form bifurcations, means mounted upon the machine for positioning said rivets when adjacent the driving position so that the slits and the bifurcations of the rivets are similarly disposed, said means including a flat member adapted to enter the slits in the rivets and provided with a wedge-shaped tip to facilitate entry thereof into said slits, and means for giving said member an intermittent motion to cause said member to enter the slits in the rivets.
5. In a rivet-driving machine having means for feeding the rivets to a point adjacent the driving position, each of said rivets having a slit lengthwise through the shank thereof to form bifurcations, means mounted upon said machine for positioning said rivets when adjacent the driving position so that the slits and the bifurcations of the rivets are similarly disposed, said means including a pivoted lever, said lever having a flat portion at one end, and means for giving said lever an intermittent motion to cause said flat portion to enter the slits in the rivets to position the same.
6. In a rivet-driving machine having means for feeding the rivets, to a point adjacent the driving position, each of said rivets having a slit lengthwise through the shank thereof to form bifurcations, means mounted upon said machine for positioning said rivets when adjacent the driving position so that the slits and the bifurcations of the rivets are similarly disposed, said means including a pivoted lever, said lever having a flat portion at one end, a rod movably mounted on said machine and engaging the other end of said lever, and means for intermittently operating said rod to give said lever an intermittent movement relative to the slits to bring the slits into the plane of said flat portion.
7. In a rivet-driving machine, said machine having a reciprocating plunger and means for feeding the rivets to a point adjacent the driving position, said position being directly beneath said plunger, each of said rivets having a slit lengthwise through the shank thereof to form bifurcations, means mounted upon said machine for positioning said rivets when adjacent the driving position so that the slits and the bifurcations of the rivets are similarly disposed, said means including a pivoted lever, said lever having a flat portion at one end, a rod movably mounted on said machine and engaging the other end of said lever, said plunger having corrugations on its exterior which engages said rod to operate said rod intermittently when said plunger is actuated, said rod giving an intermittent motion to said lever to cause said flat portion to enter the slits in the rivets to position the same.
8. In a rivet-driving machine, said machine having a reciprocating plunger and means for feeding the rivets to a point adjacent the driving position, said position being directly beneath said plunger, each of said rivets having a slit lengthwise through the shank thereof to form bifurcations, means mounted upon said machine for positioning said rivets when adjacent the driving position so that the slits and the bifurcations of the rivets are similarly disposed, said means including a pivoted lever, said lever having a flat portion at one end, a rod movably mounted on said machine and engaging the other end of said lever, said plunger having corrugations on its exterior which engage said rod to operate said rod intermittently when said plunger is actuated, said rod giving said lever an intermittent motion to cause said flat portion to enter the slits in the rivets to position the same, a spring normally pressing said rod into engagement with said corrugations, and a spring normally holding said flat portion out of engagement with the slits in the rivets.
9. In a rivet-driving machine having means for feeding the rivets to a point adjacent the driving position, each of said rivets having a slit lengthwise through the shank thereof to form bifurcations, means mounted upon the machine for positioning said rivets when adjacent the driving position so that the slits and the bifurcations of the rivets are similarly disposed, said means including a flat member and means for operating said member intermittently to cause said flat portion to enter the slits in the rivets to position the same, said flat member having a tip which is wedge-shaped and slightly twisted to form a spiral to facilitate entry thereof in said slits.
10. In a rivet-driving machine, the combination with means for feeding the rivets to a point adjacent the driving position, each of said rivets having a slit lengthwise through the shank thereof to form bifurcations.

cations, of means mounted upon the machine for positioning said rivets when adjacent the driving position so that the slits and the bifurcations of the rivets are similarly disposed, said means including a flat member and means for operating said member intermittently to cause said flat portion

to enter the slits in the rivets to position the same, said flat member having a surface canted relative to the plane of its flat. ¹⁰

In testimony whereof I affix my signature.

EDWIN B. STIMPSON.
